his attorney.

UNITED STATES PATENT OFFICE.

THOMAS A. T. YERNESS, OF CHICAGO, ILLINOIS.

EGG-CARRIER.

1,176,939.

Specification of Letters Patent. Patented Mar. 28, 1916.

Application filed September 13, 1915. Serial No. 50,390.

To all whom it may concern:

Be it known that I, THOMAS A. T. YERNESS, a subject of the Kingdom of Norway, and a resident of the city of Chicago, in 5 the county of Cook and State of Illinois, have invented certain new and useful Improvements in Egg-Carriers, of which the following is a full, clear, and exact description.

10 This invention relates to egg carriers, and its principal object is to provide a substantial card-board or paste-board structure, in which eggs may be shipped and carried without danger of breakage, although the 15 carrier may be subjected to the rough handling which it usually receives when being transported from one place to another.

Another object is to economize room, whereby a large number of eggs may be confined in a given space; to simplify devices of this class; to strengthen and reinforce parts and thereby further guard against breakage of the eggs carried by the carrier, and further to provide a carrier in which 25 the cell forming partitions are duplicates of each other.

Other objects and advantages will appear in the course of this specification and, with all of said objects and advantages in view, 30 this invention consists in the several novel features hereinafter set forth and claimed.

The invention is clearly illustrated in the accompanying drawings, in which:

Figure 1 is a plan, partly broken out, of 35 an egg carrier embodying a simple form of the present invention; Fig. 2 is a plan of one of the blanks which enters into the construction of the device; Fig. 3 is a plan of a blank from which a reinforcement member 40 is made which is also used in the construction of the device; Fig. 4 is a vertical section through two egg carrier sections showing the same in position for use; the line of section being indicated at 4—4 of 45 Fig. 1; Fig. 5 is a vertical section taken on line 5—5, Fig. 1, and, Fig. 6 is a perspective view of a fragment of the carrier.

Referring to said drawings and first to 50 Fig. 2, 10 designates one of the blanks which is used in the construction of the carrier. For a carrier holding a dozen eggs, eight blanks 10, are employed, four extending in

one direction and four at right angles thereto. Each blank 10, is formed of card-board, paste-board, or the like, and is rectangular in form. In the two side edges of said blank notches 11, are cut which have somewhat the outline of triangles, there being four notches in each side of the blank and disposed opposite to each other and reversely arranged. 55 The notches 11 are equidistant and their edges 12 are preferably rounded and the oblique edges 13 converge toward the side edges of the blank; at the corners formed by the edges 12, 13, are small notches 14, as 60 shown. Midway between the side edges of the blank are holes 15, each having somewhat the shape of an "hour-glass," the edges 16 being parallel with the side edges of the blank, and the edges 17 being parallel with 65 the edges 13 of the notches and approximately in line therewith. The blanks shown and described are folded along their median lines, indicated at α , α , in Fig. 2, and interlocked with each other in assembling them 70 into a carrier section. Associated with said blanks are reinforcing members, one of the blanks which forms a reinforcing member being shown in Fig. 3 at 18. In general, 75 said blank 18 consists of a long strip of card-board, paste-board or the like, of the same length as the blank 10, and having a width approximately equal to the sum of two of the oblique edges 17 of the hole 15. Preferably, the blank is made wider near its ends, 80 as at 19, to form overhanging portions for interlocking with the blanks 10. In assembling the parts, the blanks 18 are folded on their median lines Y—Y. Six blanks 18 are used in making a carrier for holding 12 85 eggs on each side of the carrier.

In an assembled carrier section, each blank 10, takes a V shape form in cross section, the four blanks extending in one direction, being of upright V shape and the four extending at right angles thereto being of inverted V shape, but lying in the same plane and being interlocked therewith, so that the side edge portions of each series of blanks are substantially flush with the 95 apexes of the other series, as shown. Referring to Fig. 1, the upright V blanks extend lengthwise of the sheet and the inverted V blanks extend crosswise thereof; 100

in Fig. 4 the upright V blanks of the upper section and upright V blanks in Fig. 5 are in cross section, whereas the inverted V blanks are shown in side elevation or longitudinal section.

In each carrier section, the apex portion of each V blank extends through the notches 11, of the V blanks which it intersects, it being understood that the notches of each series are in straight rows, and the two oblique halves of each V blank contact with the oblique edges 13 of the notches 11, the side edge portions being spaced a slight distance apart, as shown. The small notches 14, at the bottoms of the triangular notches 11 receive the adjacent portions of the intersecting V blanks, thus forming interlocking joints at all of the intersections between the crossing V blanks.

20 The reinforcing blanks 18 are folded on their median lines and inserted through the openings 15, which take the form of double notches opening back from the folded edges of the V blanks. The widened end portions 25 of the reinforcing blanks 18 engage with the end V blanks and prevent lengthwise movement of the reinforcing strips.

It is to be noted that the two oblique sides of any intermediate upright V blank, and 30 the adjacent sides of two intermediate intersecting, inverted V blanks form a cell or pocket *a*, of pyramidal form, for the reception of an egg; that the same intermediate upright V blank forms two adjacent oblique 35 sides for two pyramidal cells *b*, on the opposite side of the section, while the same two adjacent sides of the intermediate intersecting inverted V blanks form adjacent sides for two pyramidal cells; the cells on one 40 side of the section being staggered with respect to those on the other side.

In use, two sections are used for carrying one dozen eggs, the eggs being placed in the upper cells of one section, after which a 45 duplicate section is placed thereupon; to carry a second dozen of eggs a third section is added, the eggs being placed in the upper cells of the second section; in this way any desired number of eggs may be carried in 50 one outer inclosure by the addition of as many other sections as is required. As is customary in carriers of this class, an outer carton or box (not shown) is provided into which the packet sections are inserted.

55 In assembling the several V blanks to form a section, four upright V blanks are placed parallel to each other, properly spaced apart, and four inverted V blanks placed thereabove and transverse thereto directly over the notches 11. By pressing the oblique sides of the V blanks toward each other, the crossing blanks may be brought into interlocked condition by inserting the unnotched or apex portions of one series

into the notches 11 of the other and then 65 permitting the oblique sides to spread apart and bear against the oblique edges of said notches 11. The reinforcing strips may then be slid into the notches 15.

This egg carrier may be collapsed by 70 pressing any two diagonally opposite corners together before the two series are brought fully together; it may be found convenient to ship them, originally, in condensed form, and for this reason the carrier 75 is made collapsible.

It is to be noted that the blanks 10 may be made longer than the one shown, and that a greater number of notches 11, may be formed therein, so that a greater number 80 of egg holding cells may be had as is found desirable.

More or less variation of the exact details of construction is possible without departing from the spirit of this invention; I 85 desire, therefore, not to limit myself to the exact form of construction shown and described, but intend in the following claims to point out all of the invention disclosed herein.

I claim as new, and desire to secure by Letters Patent:

1. An egg carrier comprising a plurality of similar V-shaped cell forming members arranged in two series, those of one series 95 being inverted and crossing the other series in the same plane and interlocked therewith at the intersecting places.

2. An egg carrier comprising a plurality of similar V-shaped cell forming members 100 arranged in two series, those of each series being parallel with each other and crossing those of the other series at right angles and in the same plane, one series of V-shaped members being inverted, and both series 105 forming cells on each side of the carrier, the cells on one side being staggered with respect to those on the other side.

3. An egg carrier comprising a plurality of similar V-shaped cell forming members 110 arranged in two series, the two sides of each member being formed with notches, substantially triangular in form, one series of V members being inverted and crossing the other series, the apex portions of each series 115 entering the triangular notches and being interlocked therein.

4. An egg carrier comprising two series of similar V-shaped cell forming members, having oppositely disposed notches in their 120 side edges substantially triangular in form, and having also V-shaped notches in their apex portions midway between said triangular notches, the members of one series of V members being inverted and crossing those 125 of the other series in the same plane, with their apex portions interlocked in the triangular notches, and reinforcing strips, V-

shaped in cross section and extending through said V-shaped notches in the apex portions of the cell forming members.

5. An egg carrier comprising two similar series of V-shaped cell forming members, the members of one series being inverted and intersecting those of the other series, each cell forming member having substantially

triangular shaped notches in its side edges for the reception of the apex portion of the 10 intersecting V-shaped cell forming member, said intersecting members forming pyramidal cells on each side of the carrier, those on one side being spaced from and staggered with respect to those on the other side. 15

THOMAS A. T. YERNESS.
